JAMES CAMROD LEDBETTER, OF NEW YORK, N. Y., ASSIGNOR TO THE PROSPERITY COMPANY, INC., OF SYRACUSE, NEW YORK, A CORPORATION OF NEW YORK

POWER PRESS

Application filed March 30, 1928. Serial No. 265,833.

This invention relates to pressing machines and more particularly to garment presses of the power type: and an object is to produce a power press operating under 5 fluid pressure as, for example, air or steam. According to the principles of this invention, a high powered press is operated from the same source of steam which is ordinarily employed to heat the press jaws and steam 10 spray the work.

A further object is to produce a diaphragm-type of power press of simple construction wherein a heating chamber and a steam and air spray chamber is formed in 15 one and the same pressing member or jaw without any separation or space between the two chambers.

A further object is to produce a power press having coacting press jaws and operating means therefor which opens and closes 20 the press and wherein one jaw is adapted as a power jaw, one surface of which forms a press plate to engage the work and the other surface of which includes a fluid-expansive motive-power compression chamber. This power jaw further includes a steam 25 and air spraying chamber as well as a heating chamber formed between the press plate and the compression chamber.

Other objects of the invention are made 30 apparent from the description and accompanying drawings wherein;

Figure 1 is a side view of a conventional 35 form of press showing two coacting press jaws, one of which is made in accordance with this invention to form a power jaw, the latter jaw being in section as taken on the line 1—1 of Figure 2.

Figure 2 is a rear edge or side elevation 40 of the power jaw removed from the press with one end thereof broken away.

Figure 3 is a front view of Figure 1, the power jaw being in longitudinal section as taken on the line 3—3 of Figure 1.

Figure 4 is a longitudinal section of the power jaw removed from the other parts of the press and showing the diaphragm or fluid-expansive motor means distended or expanded to move the jaw with great force 45 against the work.

Referring further to the views, there is shown a press frame 6 carrying a table 7 for the work and stationary press buck or lower jaw 8. The upper pressing member or head includes a power press jaw 9 which I have 55 shown of integral construction formed in one piece but which may be built up in any well known manner by securing two or more castings or steel stampings together by which to form the several necessary chambers 60 therein as will be explained. The power jaw 9 is shown in the drawings as forming the press head, i. e. the upper press jaw, but it is to be understood that the power jaw 9 may also be mounted on the frame 6 and 65 thus become the stationary buck or lower pressing member.

Presses of this type for general work such as garment and laundry pressing, ordinarily 70 have one movable press jaw, as for example the head 9; and to this end an operating member such as a press lever 11 is pivoted at 12 on the frame 6 and reaches forward where it is bolted at 13 to a motor means cover 14 placed over a fluid-expansive dia- 75 phragm forming part of the power jaw 9. The operating member 11 swings on its pivot 12 to raise and lower the head 9 in relation to the buck 8 and the work is pressed between the two jaws 8 and 9. The press 80 lever and cover form a stationary support means 11—14 after the press is closed and which resists the force of the motor means so that reaction of the latter causes the power 85 jaw to be forced against the other jaw.

The power jaw 9 is so constructed as to provide a press plate 16 on one side thereof, perforated at 15, and adjacent to which is formed a steam and air spray chamber 17. Immediately adjacent the foraminous spray 90 chamber 17 is formed a closed heating chamber 18 into and through which steam is circulated to raise the press jaw 9 to high temperature. This jaw 9 may be ribbed at 19 so as to efficiently conduct heat from the heating chamber 18 to the press plate 16 and make a rigid jaw construction.

The upper or outer face of the power jaw opposite the press plate may be depressed, as indicated at 21, to form a motive-power

fluid-expansive compression chamber 21. A flat disc type corrugated flexible metallic diaphragm 22 is usually made circular in form and has its outer edges sealed onto the face of the power jaw 9 and over the compression chamber 21 by using a ring or other means 23. The diaphragm 22 encloses the steam expansive compression chamber 21 which is comparatively small in volume and thus requires little steam to operate the power jaw. A fluid inlet 24 extends laterally from one edge of the jaw into the compression chamber 21 to supply steam to expand the diaphragm 22. The compression chamber preferably slopes toward the fluid inlet passage 24 so as to drain water forming therein back into the steam connections.

A stationary member in the form of the cover 14 is mounted over the diaphragm 22 and over its enclosed steam compression chamber 21. The cover 14 is made with a rim 26 which fits down over the diaphragm 22 and encloses it. The press lever 11 or frame 6, as the case may be, is bolted at 13 to the cover 14. The press lever or operating means 11 stands rigid and stationary above the press when it is closed lightly on the work so that when the power jaw is actuated, the press lever 11 and cover 14 takes the strain thereby forcing the power jaw against the work on the buck 8.

In the example of the press shown the power jaw 9 is attached to the press lever so that the jaw is raised off the work by this press opening and closing means 11. In order that the jaw 9 be lifted with the lever 11 and at the same time be capable of short movement power strokes in relation thereto, I provide ears 28 on the cover through which a bolt 29 is freely passed and anchored to the jaw 9. A compression spring 30 is confined between the ear 28 and nut 31. This spring 30 withstands compression sufficiently to lift the press jaw 9 when the cover 14 and press operating lever 11 are raised. However the compression spring 30 yields under the expansion of the diaphragm to permit the jaw 9 to move with great force in relation to the cover 14. This yieldable connection 29-30 attaches the power jaw to the press operating means 11 for slight relative motion therewith.

In forming the compression chamber 21, it may be considered that the circular flange 33 is raised on the surface of the power jaw so as to provide the compression space or chamber 21, and the fluid pressure tight diaphragm 22 is sealed thereon by screw fastening or otherwise anchoring it to this flange 33. The diaphragm 22 therefore closes a comparatively shallow fluid expansive chamber 21. The cover rim 26 fits down over the flange 33 and this arrangement affords guided movement between the cover and power jaw. This construction places the

flange 33, the compression chamber 21 and the diaphragm 22 up in the cover 14 so that the diaphragm and steam expansion chamber 21 are well enclosed.

The cover 14 engages the center portion of the diaphragm 22 and forms a stationary force resisting member against which the diaphragm expands and reacts. When steam is admitted into the compression chamber 21, it follows that the steam expands therein and the stationary force resisting cover 14 withstands the force of the pressure, whereas the movable jaw 9 is free to move relatively of the cover within the rim 26 and against the work on the buck 8.

Any suitable means of supplying steam to the compression chamber 21 may be employed and by way of example there is shown a flexible connection 35 transmitting steam from a supply pipe 36 into the inlet passage 24 and hence to the compression chamber. A three-way throttle and exhaust valve 37 is provided in the steam supply system to admit steam into the compression chamber 21 and to exhaust it therefrom. Operator-actuated means of any suitable form is required to work the three-way valve 37, and to this end a valve controlled handle 38 connects with a link 39, the latter being connected through a bell crank 40 to the motor means control valve 37.

After the work is spread upon the lower jaw 8 the press is closed on the work under light initial pressure. The valve 37 is now opened thereupon admitting steam into the chamber 21, and the steam expanding therein pushes down on the power jaw 9 sliding it in relation to the cover to produce high pressure on the work. The center portion of the diaphragm 22 reacts with great force from the stationary force resisting cover member 14 and operating member 11. The corrugated portions of the diaphragm readily flex thereby permitting the outer edges of the diaphragm to move downwardly with the power buck 9 while the center portion of the diaphragm is tightly pressed against the force resisting stationary cover 14. The springs 30 compress to allow the power jaw and press plate 16 to execute a quick high compression stroke against the work on the buck 8.

To release the jaw compression from the work between the head and buck, the operator works the valve 37 in the other direction which exhausts the steam from the compression chamber 21 and through the exhaust pipe 25, whereupon the compressed springs 30 expand and return all parts to normally non-pressing position.

A particular advantage in this construction resides in the fact that the diaphragm 22 and its compression chamber 21 are spaced from the foraminous press plate 16, spray chamber 17 and the heating chamber 18. In this way the heating chamber 18 is readily

located in close proximity to the spray chamber 17 and hence raises the spray chamber to a high temperature, since the two chambers can be closely related, the motor means 21—22 being placed out of the way. In the 5 form of the invention shown, the diaphragm motor means is placed exteriorly and on the upper or outer surface of the press head; or if the press head is inverted to form a buck, 10 then in this latter case the motor means would be located on the bottom surface of the press jaw.

This type of power press provides one 15 wherein the motor means is concealed within and carried by one of the jaws and the motor means is simple in construction requiring a minimum number of working parts and is convenient for use because it employs steam from the same source 20 which is used to heat the jaw by filling and circulating through the heating chamber 18 and which is used to spray the work by discharging through the press plate 16.

Another advantage of this power jaw 25 resides in the fact that the yielding spring connecting means 29—30 connects the power jaw to the press lever 11 or cover 14 in such a way that mobility of the power jaw against the work is attained. Unevenness of the work 30 or inequality of thickness does not impose unequal strain on the press jaws. If work is thicker at one end than the other, the jaw compensates for that unevenness by reason of the flexible spring connection made between 35 the movable press jaw 9 and its supporting means 11—14. The power jaw wobbles or tilts longitudinally or laterally to attain the same pressure against a thin portion of the work as against a thick portion.

In the example of the invention illustrated, 40 the fluid-expansive motor means 21—22 is concealed by the cover or cap 14—26 which is interposed between the press member 11 or any other member provided to hold the 45 cover and the power jaw. This cover is bolted to the spaced parallel lever parts 11 and stiffens the lever construction, or may be made integral therewith.

I have therefore produced a power jaw 50 which includes closely related steam heating and work spraying chambers 17 and 18 placed adjacent the working face or press plate 16, this being accomplished by placing the simple fluid-expansive motor on the opposite face of the power jaw. In this way, 55 the frame and remaining press parts are simplified in construction because they are free of mechanism.

What is claimed is:

60 1. A press comprising, cooperating jaws and an operating member attached to one jaw to move the same, the movable jaw including a press plate provided with a motive-power fluid-expansive compression chamber, a circular 65 flexible disc diaphragm sealed over the

compression chamber, a circular cover carried with the operating member and disposed over the compression chamber and against which the diaphragm reacts, and means movably connecting the cover to the movable jaw.

2. A press comprising, coacting press jaws and operating means to open and close the press, one of which jaws is a power jaw provided with a motive-power fluid-expansive compression chamber, a disc diaphragm placed over the compression chamber and having its outer periphery sealed to the power jaw, a force resisting member placed over the diaphragm and against which the latter reacts to move the power jaw with great force against the other jaw, and means to attach the power jaw for movement in relation to the force resisting member.

3. A press comprising, coacting press jaws and operating means to open and close the press, one of which jaws is a power jaw, a cover including a rim and means attaching the power jaw to the cover for movement in relation thereto, said power jaw being provided with a fluid-expansive compression chamber which fits into the cover within the rim, and a disc corrugated flexible metallic diaphragm inclosed within the cover and the periphery of the diaphragm and being sealed to the power jaw over the compression chamber, the center of the diaphragm engaging the center of the cover and reacting thereupon to move the power jaw against the other jaw.

4. A press comprising, coacting press jaws and operating means to open and close the press, one of which jaws is a power jaw, a flange raised on the power jaw, a flat corrugated flexible diaphragm having its periphery sealed to the flange and forming a fluid-expansive compression chamber between it and the jaw, a cover placed over the diaphragm and including a rim slidably fitting the flange, and said jaw being provided with a fluid inlet extending laterally from an edge of the jaw into the compression chamber.

5. A press comprising, coacting press jaws and operating means to open and close the press, one of which jaws is a power jaw, said power jaw having a press plate to engage the work and having a surface opposite the press plate which is depressed to form a motive-power compression chamber, a flat flexible diaphragm placed over the compression chamber and having its periphery sealed thereto, said power jaw being provided with a fluid-pressure inlet extending from an edge thereof and running parallel to the diaphragm and connecting with the compression chamber, and a member placed over and against which the diaphragm reacts to move the jaw against the other jaw.

6. A press comprising, coacting press jaws and operating means to open and close the

press, one of which jaws is a power jaw having an outer depressed surface, a disc diaphragm having its outer edge sealed to the jaw and positioned over the depressed surface thereby forming a closed fluid-expansive compression chamber, a fluid-pressure inlet passage formed in the jaw extending from its edge to the compression chamber, and a force resisting cover disposed over the diaphragm and against which the latter reacts to force the jaw power against work upon the other jaw.

7. A press comprising, coacting press jaws and operating means to open and close the press, one of which jaws is a power jaw provided with a fluid chamber inside thereof and adjacent one surface thereof, and a compression chamber formed outside the jaw on the opposite surface, a disc diaphragm sealed to the jaw over the compression chamber, a fluid entry passage being formed in the jaw and communicating with the compression chamber, and a force resisting member against which the diaphragm reacts to move the power jaw against the other jaw.

8. A press comprising, coacting press jaws and operating means to open and close the press, one of which jaws is a power jaw including a foraminous press plate, and being provided interiorly with a spray chamber and a heating chamber adjacent the press plate, a compression chamber provided exteriorly on the outside surface opposite the press plate, a flexible diaphragm sealed on the jaw over the compression chamber, and a force resisting member against which the diaphragm reacts to force the movable jaw against the other jaw.

9. A press comprising, coacting jaws and operating means to open and close the press, one of which jaws is a power jaw including a foraminous press plate formed on one surface, a compression chamber being provided on the other surface, a disc diaphragm sealed to the jaw over the compression chamber, a force resisting member disposed over and against which the diaphragm reacts to force the power jaw against the other jaw, and a fluid heating chamber and spray chamber being provided inside the power jaw between the compression chamber and the press plate.

10. A press comprising, coacting press jaws and operating means to open and close the press, one of which jaws is a power jaw including a foraminous press plate, a spray chamber being formed therein adjacent the press plate, a heating chamber being formed therein adjacent the spray chamber, a compression chamber being formed therein adjacent the heating chamber, a disc diaphragm having its periphery sealed to the power jaw over the compression chamber, and a force resisting member disposed across and against which the diaphragm reacts to force the power jaw against the other jaw.

11. A press comprising, coacting press jaws and operating means to open and close the press, a circular cover including a downwardly directed rim and the cover being carried with the operating means, a power jaw press plate including a circular compression chamber disposed within the cover and the jaw includes guide means movably fitting the rim, a circular disc diaphragm sealed over the compression chamber within the cover, said diaphragm engaging the cover and reacting therefrom to force the press plate away from the cover, and a yielding connection made between the cover and power jaw.

12. A press as defined in claim 11 wherein the yielding connection comprises ear means formed on the cover, said ear means being formed with apertures therethrough, a guide bolt anchored to the power jaw and movable through each aperture in the ear means, and spring compression means carried on the bolt engaging the ear means to normally draw the power jaw toward the cover.

13. A press comprising, a frame and press lever pivoted thereon, a power jaw, a cover interposed between the power jaw and press lever and carried with the lever, means yieldingly attaching the power jaw to the cover, a disc diaphragm under the cover having its center resting against the cover and its periphery sealed to the power jaw forming a compression space adjacent the power jaw, means to convey fluid pressure into the compression space, and another jaw against which the power jaw compresses.

In testimony whereof I affix my signature.
JAMES CAMROD LEDBETTER.
